UNITED STATES PATENT OFFICE.

JAMES E. COLLINS, OF DANVERS, MASSACHUSETTS, ASSIGNOR TO UNITED SHOE MACHINERY COMPANY, OF BOSTON, MASSACHUSETTS, A CORPORATION OF NEW JERSEY.

HEEL-NAILING MACHINE.

No. 823,582.

Specification of Letters Patent.

Patented June 19, 1906.

Application filed August 12, 1904. Serial No. 220,447.

To all whom it may concern:

Be it known that I, JAMES E. COLLINS, of Danvers, county of Essex, State of Massachusetts, have invented an Improvement in Heel-Nailing Machines, of which the following description, in connection with the accompanying drawings, is a specification, like characters on the drawings representing like parts.

10 In the manufacture of shoes or slippers having wooden heels, or what are generally known as "French" heels, which are usually made of wood, it has been customary to attach the heels to the heel-seat of the shoe by driving the heel-nails by hand from the inner side of the shoe into the heel, it being impossible to secure them by means of an ordinary heel-nailing machine, which drives all the nails simultaneously, as the heel would be

20 broken or split.

My invention has for its object to provide an improved means for securing a wooden heel to the heel-seat of a shoe, to reduce the cost of performing this part of the process by facilitating its performance, and to enable the heels to be secured with greater uniformity or accuracy.

25 In carrying out my invention I employ suitable means for sustaining a shoe and heel in such relation that the heel will be in alignment with the heel-seat of the shoe. A nail-driving device for driving nails into the heel is provided and is arranged to enter the shoe. The construction is such that relative movement of the nail-driving device and shoe-sustaining means is permitted to allow nails to be inserted successively at the points desired in the heel. In the machine shown a nail-delivering nozzle is mounted in stationary position and the shoe and heel sustaining means is freely movable in a direction transverse to the path of the nails both laterally and longitudinally of the heel. The shoe-sustaining means is manually controlled 40 and manipulated to advance the work to the extent desired after each insertion of a nail.

Other features of the invention will be hereinafter described.

50 In the drawings, Figure 1 illustrates in side elevation a machine embodying my invention. Fig. 2 is a longitudinal central sectional view of the shoe and heel support, and Fig. 3 is a plan view thereof. Fig. 4 is a de-

tail end view of one of the heel-clamps. Fig. 5 is a section on the line *d d* of Fig. 2. Figs. 55 6 and 7 are enlarged sectional plan views on the line *a a* of Fig. 1. Figs. 8 and 9 are sectional views on the line *b b* of Fig. 1. Fig. 10 is an elevation of the end of the tack-driver nozzle, and Fig. 11 is a section on the line *c c* 60 of Fig. 10.

In carrying out my invention I may employ any well-known form of machine which is adapted to force nails from the throat of a nozzle by means of a driver into the work, 65 which is held against the end of the nozzle. As such devices are common in the art a special description thereof is deemed unnecessary. Such a machine is indicated by the numeral 1 in Fig. 1 and is provided with a 70 nail-ejecting nozzle 2, which for my purposes I make somewhat longer than is necessary for simply driving nails into the sole or heel of a shoe from the outside. Said nozzle is provided with the usual driver 2', which is 75 adapted to be moved to the face of the nozzle when each nail is driven. The nail-driving mechanism is controlled by any suitable means, as the foot-lever 3. The lower end of the nozzle 2 is provided with a semicircular guard 4, the face or under side of which is upwardly curved from the end of the throat for the purpose hereinafter described.

80 A support or holder 5 is rigidly secured to the upper end of a rigid rod 6, the latter having a ball-and-socket connection with a weighted foot-lever 7, the weight on said lever being arranged to lift said rod and parts supported thereby when the pressure on the treadle of lever 7 is removed. A pair of heel-clamping levers 8 are pivotally mounted at 8' on the support 5, said levers having jaws 9, the faces of which are adapted to engage the sides of a wooden heel, so that when said jaws are moved together a heel may be firmly 95 clamped between them with its bottom or top lift resting on the top of said support 5. A cam 10 is mounted between the rear ends of said levers, and an arm 11 is connected thereto, so that said jaws may be readily 100 locked together. A vertical arm 12 is mounted on each lever 8, and each arm has a horizontal spring-finger 13 secured thereto, said fingers extending forwardly divergently directly above and equidistant from the faces 105 of jaws 9. Said fingers are shaped to corre-

spond to opposite sides of a shoe-counter and are so arranged that when the heel portion of a shoe is placed therebetween and pressed onto a heel held between said jaws 5 the shoe and heel will be held firmly in the exact position with relation to each other that they should be in when attached.

The front end of the support is provided with clamps 14, which are slideable transversely thereof and are adapted to engage opposite edges of the sole and to hold the same against forward and transverse movement, means being provided for moving said clamps toward each other simultaneously, 15 consisting of an oppositely-threaded bolt 15, which is journaled in the under side of said support and is provided with a handle 16, with which it may be readily rotated.

A bracket 17 is secured to the frame near 20 the support and is provided with an enlarged aperture 17', through which rod 6 passes. A pair of clips 18, having corresponding semicircular recesses in their adjacent edges, are adapted to be secured to the upper side of 25 said bracket to constitute a bearing for rod 6.

The operation of my device is as follows: The support 5 is first drawn down by depressing the treadle of lever 7, and then the jaws 9 are opened. A heel is then placed between 30 the jaws and a shoe which is to be heeled is placed thereon with its heel end between the spring-fingers 13 and its heel-seat in position on the heel. The fore part of the shoe is also preferably secured in place by the clamps 14. 35 The weighted lever 7 is then permitted to lift the support 5, so that the face of the nailing-nozzle 2 engages the inner side of the shoe directly above the heel-seat. If the heel to be secured is an ordinary French heel 40 or heel in which the bottom side is much smaller than the side which comes next the heel-seat, then it will not be desirable to have the nails driven into the heel at points which are not directly above its bottom side. In 45 such instance, therefore, I secure the clips 18 to the bracket 17, so that the supporting-rod 6 is located in the semicircular recesses thereof and is rotatably mounted therein, the nail passage or throat of the nozzle being eccentric to the axis of said rod. The weight of 50 the lever 7 is sufficient to press the inner side of the shoe against the nozzle 2 of the nailing-machine with such force that the nails will be driven through the sole or inner sole of the shoe into the heel. After the nailing-machine drives in each nail the shoe is turned or 55 rotated a short distance by the operator, so that a circular row of nails will be driven into the heel when the shoe has been given a single revolution, as indicated in Fig. 9. In 60 case a wooden heel of the shape commonly employed on men's shoes is to be secured and in which case the nails may be driven close to the edge of the heel the clips 18 are 65 removed, so that the bar 6 may be swung to

a considerable extent within the aperture 17' of the bracket 17. Assuming that the parts are moved to the positions illustrated in Figs. 6 and 8, so that the edge of the guard 4 at the end of the nozzle 2 bears against the inner side of the upper, (see Fig. 8,) the shoe will be drawn forward, then moved sidewise, then backwardly, and then sidewise back to the initial position, so that a series of nails will be driven in the line represented by the 70 arrows in Fig. 8. The guard 4 will prevent the nails from being driven within a certain distance from the upper and permits the nails to be driven in even with the surface of the inner sole. The closeness with which the 75 nails are driven together will be controlled by the operator. In this manner the heel will be rigidly secured to the shoe in much less time than it is possible to perform the same operation by hand, and moreover the heels 80 will be secured with more uniform accuracy than they are likely to be when secured by hand.

Having described my invention, what I claim as new, and desire to secure by Letters 90 Patent of the United States, is as follows:

1. A heel-nailing machine, comprising means for sustaining a shoe and heel in attaching position, and a nail-driving device for driving nails into the heel having a nail-delivering nozzle to enter the shoe, said sustaining means and nail-driving device being arranged for relative movement in a direction transverse to the path of the nails.

2. A heel-nailing machine, comprising 100 means for sustaining a shoe and heel in attaching position, a nail-driving device for driving nails into the heel having a nail-delivering nozzle to enter the shoe, said sustaining means and nail-driving device being arranged for relative movement in a direction transverse to the path of the nails, and means 105 for restricting said relative movement to a predetermined limit.

3. A heel-nailing machine, comprising 110 means for sustaining a shoe and heel in attaching position, and a nail-driving device for driving nails into the heel having a nail-delivering nozzle to enter the shoe, said sustaining means and nail-driving device being arranged 115 for relative movement laterally and longitudinally of the heel whereby the attaching-nails may be successively inserted over approximately the entire area of the heel.

4. A heel-nailing machine comprising an 120 upright heel-support having at its upper end means for holding the shoe upright in position on the heel, nail-driving devices having a depending nail-delivering nozzle adapted to enter the shoe above the heel, and means permitting rotary movement of said support about a center which is eccentric to the 125 throat of said nozzle, substantially as described.

5. A heel-nailing machine comprising an 130

- upright heel-support having at its upper end means for holding the shoe upright in position on the heel, nail-driving devices having a depending nail-delivering nozzle adapted to 5 enter the shoe above the heel, means permitting universal transverse movement of said support, and stationary guiding devices surrounding said support for limiting said movement, substantially as described.
6. A machine of the character described, comprising a pair of heel-clamping jaws, and means for moving them into locking engagement with a heel, a pair of diverging spring-actuated fingers, one secured to each jaw and 10 movable therewith, the faces of said fingers being equidistant from the faces of said jaws for centering the heel portion of the shoe in position over the heel while held by said jaws, and nail-driving means having its delivering- 15 nozzle located between said fingers, substantially as described.
7. A machine of the character described, comprising a rotatably-mounted support, a pair of heel-clamping jaws mounted on said support and movable transversely thereof, a 20 pair of diverging fingers carried by said sup-
- port and arranged directly above said jaws and equidistant therefrom for centering the heel end of the shoe on the heel as it is held by said jaws, a fore-part holder in front of said jaws on said support, and a nail-driving means having its delivery-nozzle between 30 said fingers, substantially as described.
8. A machine of the character described, comprising a heel-support, a shoe centering 35 and holding means directly above said support for holding the shoe in position on a heel held by said support, and a nail-driving means having its delivery-nozzle arranged to enter the shoe above the heel, said nozzle having a transversely-extending guard at its end, the edge of said guard being curved and the face thereof being upwardly beveled from the throat of the nozzle to said edge, substantially 40 as described.
- In testimony whereof I have signed my name to this specification in the presence of two subscribing witnesses.
